[57] ABSTRACT

In an ice-skate of the kind having a longitudinally-extending tubular reinforcing member for the blade and a pair of cup-shaped support members extending from the tube to a bed-plate and a sole-plate for a skate boot, the lower ends of the cup shaped members are formed with flanges having a semi-cylindrical cross-section so that they wrap completely around the tubular member, up to the blade.

Fig. 1.

Fig. 2.

ICE SKATES

This invention relates to ice skates, especially skates for hockey players.

Such skates are usually constructed with a heavily constructed boot and a reinforced blade, with at least two support members extending upwardly from the blade to the boot. In a typical construction the support members are in the form of inverted, generally frustoconical cups which are attached at their lower ends to a tubular reinforcing member which extends along the length of the tube. The lower ends of the cup-shaped members are usually attached to the sides of the tubular member by means of extensions which are spot-welded to the tubular member, which is also being spot-welded to the blade. The upper ends of the two cup-shaped members are attached respectively to a heel-plate and a sole-plate beneath the boot.

A disadvantage of this type of construction is that a large and undesirable load is imposed on the spot-welds, and there is only rather a low resistance to relative twisting between the cup and the tube.

It is an object of the invention to overcome these disadvantages, by providing a cup-to-tube joint of greater strength and rigidity.

A tube-skate of the type described in accordance with the invention has the extensions of the cup-shaped members formed to wrap completely around the tube up to the blade. This strengthens the skate against side thrusts and helps to relieve the spot welds from undue loads, and may obviate the need for spot-welding to the tube, entirely.

Further strength and improved sealing of the joint can also be achieved by running soft solder into the interior of the cup during assembly.

An embodiment of the invention will now be described by way of example with reference to the accompanying drawings, in which:

FIG. 1 shows a side elevation of part of a skate according to the invention; and,

FIG. 2 shows an enlarged cross-section on the line II — II of FIG. 1.

Referring to the drawings, the blade 2 of the skate has a reinforcing tube 4 attached to it by means of flanges 5 extending from the tube and rivets 6. The front end 8 of the blade is upturned. Deep-drawn cups 10 are attached to the tube by means of extensions 12 of the cups which wrap around the tube as shown in detail in FIG. 2, to a position where they abut the sides of the flanges 5 at 14. These extensions may be spot-welded to the tube as at 13.

Additional strength and sealing of the joint are achieved by running soft solder into the cup during assembly, as indicated at 16.

Since the ends of the extensions 12 abut directly 55

against the tube flanges, they provide resistance to twisting of the cups relative to the tube and thus a substantial part of the load is taken off the spot-welds. The complete wrapping round of the extensions also improves the overall strength by producing an effectively double-walled tube.

The strength of this arrangement is such that the solder run into the cup during assembly may be sufficient to hold the structure together, and spot-welding of the tube, with the associated stress concentrations it produces, may be avoided.

I claim is:

1. An ice skate comprising: a skate boot; a heel plate and a sole plate for the boot; a blade; a longitudinally extending tubular reinforcing member having a pair of downwardly extending flanges fixed to the top edge of the blade; a cup-shaped support member extending between the tubular member and the sole plate; and a further cup-shaped support member extending between the tubular member and the heel plate; a pair of downwardly extending flanges at the lower end of each cup-shaped member, for attachment to the tubular member; wherein the downwardly extending flanges form a cylinder completely surrounding the portion of the tube immediately below each support member up to the tube flanges, the cylinder having a longitudinal aperture through which the tube flanges protrude; the diameter of the base of the support cup being less than the diameter of the tube, whereby the cylinder closely embraces the major portion of the circumference of the tube below the cup member.

2. An ice-skate according to claim 1 further comprising a soldered joint between the cup flanges and the tube.

3. An ice skate comprising: a skate boot; a heel-plate and a sole-plate for the boot; a blade; a longitudinally extending tubular reinforcing member having a pair of downwardly extending flanges fixed to the top edge of the blade; a cup-shaped support member extending between the tubular member and the sole-plate; and a further cup-shaped support member extending between the tubular member and the heel-plate; a pair of downwardly extending flanges at the lower end of each cup-shaped member, for attachment to the tubular member; wherein the downwardly extending flanges form a cylinder completely surrounding the portion of the tube immediately below each support member up to the tube flanges, the cylinder leaving a longitudinal aperture through which the tube flanges protrude; the diameter of the base of the support cup being less than the diameter of the tube, whereby the cylinder closely embraces the major portion of the circumference of the tube below the cup member, and the cylindrical flanges being spot-welded to the tube.
